Des. 240,280

Patented June 15, 1976

240,280

SPORT SHOE

Jonas Senter, Greenwich, Conn., assignor to CITC Industries Inc.

Filed Oct. 15, 1974, Ser. No. 515,033

Term of patent 14 years

Int. Cl. D2—04

U.S. Cl. D2—310

FIG. 1

FIG. 2

FIG. 3

FIG. 4

FIG. 6

FIG. 10

FIG. 8

FIG. 1 is a right front perspective view of a sport shoe showing my new design;

FIG. 2 is a top plan view thereof;

FIG. 3 is a left side elevational view thereof;

FIG. 4 is a rear elevational view thereof;

FIG. 5 is a right front perspective view of another embodiment of my new design of FIG. 1;

FIG. 6 is a top plan view thereof;

FIG. 7 is a left side elevational view thereof;

FIG. 8 is a rear elevational view thereof;

FIG. 9 is a right front perspective view of yet another embodiment of my new design of FIG. 1;

FIG. 10 is a top plan view thereof;

FIG. 11 is a left side elevational view thereof; and

FIG. 12 is a rear elevational view thereof.

I claim

The ornamental design for a sport shoe, as shown and described.
